INSULATED CONNECTOR

Norimitsu Irie, Kawasaki, Japan, assignor to
AMP Incorporated, Harrisburg, Pa.

Filed Oct. 18, 1971, Ser. No. 189,855

Claims priority, application Japan Apr. 27, 1971

Term of patent 14 years

Int. Cl. D13—03

U.S. Cl. D26—1 A

FIG. 1.

FIG. 4.

FIG. 2.

FIG. 3.

FIG. 5

FIG. 6.

FIG. 1 is a side view of the insulated connector showing my new design;

FIG. 2 is a top plan view thereof;

FIG. 3 is a bottom plan view thereof;

FIG. 4 is an end view thereof;

FIG. 5 is a perspective view from above and one side of FIG. 1; and

FIG. 6 is a perspective view from below and the other side of FIG. 1.

I claim:

The ornamental design for an insulated connector, substantially as shown.
